UNITED STATES PATENT OFFICE.

WILLIAM B. LODGE, OF DANBURY, CONNECTICUT.

IMPROVEMENT IN FULLING-MILLS.

Specification forming part of Letters Patent No. 93,100, dated July 27, 1869; antedated July 23, 1869.

To all whom it may concern:

Be it known that I, WILLIAM B. LODGE, of Danbury, in the county of Fairfield and State of Connecticut, have invented a new and useful Improvement in Fulling-Machines; and I do hereby declare that the following is a full, clear, and exact description of the same, reference being had to the accompanying drawings, forming a part of this specification.

This invention consists in certain novel means of heating the trough of a fulling-mill and its contents, and of supplying water thereto and drawing it off therefrom during the fulling or felting process.

Referring to the accompanying drawings, Figures 1 and 2 represent sectional elevations of a fulling-mill constructed according to my improvement, taken at right angles to each other; and Fig. 3 is a sectional view of a portion of the heating apparatus, showing the manner of heating the bottom of the trough.

Similar letters of reference indicate corresponding parts in the several figures.

A is the frame of a fulling-mill, having provided therein the usual curvated trough, B, in which are made to operate, by any suitable means, mallets C C, all substantially after the usual manner of constructing fulling-mills.

a a are pipes communicating with a conveniently-arranged steam-boiler and designed for admission of steam or water, or both, into a steam-chest, E. Said steam-chest E is constructed of copper or other metal, and is arranged at the bottom of the trough B, near the lowest point thereof, and in a manner as represented in the drawings. This steam-chest is of a rectangular elongated formation; but may be of any suitable form, and is provided, longitudinally through its center, with a partition, f, forming therein two parallel compartments, o o, which communicate with each other through said partition at a point, e, so that the steam or water admitted therein from the pipe a will have to traverse the entire length of both compartments o o before it can leave the chest, thereby heating the lower portion of the trough B across its entire breadth in a uniform manner. Said steam-chest E may, if preferred, consist simply of a continuation of the pipe a, passing in as far as the point e and

doubling back any number of times, to produce the requisite degree of heat, and this I consider an equivalent of the steam-chest E, already described.

c is an exhaust-pipe for the steam-chest E, or may be a continuation of the pipe a, when the steam-chest is dispensed with by the substitution of the pipe a, passing in and doubling back as described. This pipe c is made to pass upwardly from the steam-chest E and turn in a horizontal direction across the top of the trough B, and has provided, in the underside of said horizontal portion, a series of perforations, i, as shown in Fig. 2, so that steam or condensed steam or water may be admitted from the chest E into the trough B from a point above the material that is being fulled, thereby not only heating the upper portion of the trough and fabrics simultaneously with the lower portion, but also by this means the clogging or filling up of the perforations i by the accumulation of dirt or other sediment at the bottom of the trough is obviated. The supply of steam and water admitted from the boiler to the steam-chest, as also from the steam-chest to the horizontal showering-pipe c', may be regulated to any desirable adjustment or shut off entirely by means of suitably-arranged valves or cocks, thereby to regulate the temperature of the trough and also the quantity of steam or water admitted within the trough. The water or condensed steam, when not being used within the trough, may be discharged through a cock, g, provided in the lower part of the pipe c.

G is a draining-chamber, arranged at the bottom of the trough B, near the lowest point thereof. Said draining chamber G is made to extend the entire width of the trough, as represented, and is provided with a perforated top, m, so that the water may be drawn from the trough simultaneously along the entire length of the chamber, thereby draining the fabrics in a uniform manner.

Hitherto the felting or fulling with soap has been considered the best. By this process a firmer and more pliable felting produced without soap and in less time. Again, fur waste may be more thoroughly worked into hat-bodies by this improvement, making it homo-

geneous throughout, thereby producing heavier material and a material that finishes up better.

What I claim as my invention, and desire to have secured by Letters Patent, is—

1. The combination of the steam-chest E and the showering-pipe *c c'* with the chamber B, arranged and operating substantially as and for the purposes herein set forth.

2. The perforated draining-chamber G, arranged all across the trough, substantially as and for the purpose herein set forth.

WILLIAM B. LODGE.
